CLAIM

The ornamental design for a split flow diffuser for an aquarium, as shown.

DESCRIPTION

FIG. 1 is a front perspective view of a split flow diffuser for an aquarium, showing my new design;

FIG. 2 is a front elevational view thereof;

FIG. 3 is a rear elevational view thereof;

FIG. 4 is a left side elevational view, the right side being a mirror image thereof;

FIG. 5 is a cross-sectional view taken along line 5—5 of FIG. 4;

FIG. 6 is a top plan view thereof; and,

FIG. 7 is a bottom plan view thereof.

The broken line showing is for illustrative purposes only and forms no part of the claimed design.
